(57) **ABSTRACT**

A magnetic element is provided and includes a first magnetic core, a second magnetic core and two windings. The first magnetic core is made of a first material and includes two winding pillars and two connecting parts. The first magnetic core has a first permeability. The second magnetic core is made of a second material and has a second permeability. The first permeability is less than the second permeability. When the current flows through the two windings, a closed magnetic path is generated in the first magnetic core, the magnetic flux generated by the closed magnetic path flows through one of the winding pillars, one of the connecting parts, the other one of the winding pillars and the other one of the connecting parts in a direction, and the magnetic fluxes generated on the second magnetic core are cancelled out by each other.

MAGNETIC ELEMENT

CROSS-REFERENCE TO RELATED APPLICATION

This application claims priority to China Patent Application No. 202111085268.6, filed on Sep. 16, 2021, the entire contents of which are incorporated herein by reference for all purposes.

FIELD OF THE INVENTION

The present disclosure relates to a magnetic element, and more particularly to a magnetic element for interleaved parallel circuit.

BACKGROUND OF THE INVENTION

The conventional power supply has increasingly strict requirements on power efficiency. Further, in 2023, 80 PLUS titanium efficiency specifications will be introduced to improve energy efficiency.

For the magnetic element used in the conventional power supply, the winding pillars and the center pillar are alloys of the same material. Therefore, when the current flows through the windings on the two winding pillars, the magnetic flux generated on the center pillar are superimposed. The causing loss of the magnetic element is increased, and the conversion efficiency is decreased.

Therefore, there is a need of providing a magnetic element to obviate the drawbacks encountered from the prior arts.

SUMMARY OF THE INVENTION

It is an object of the present disclosure to provide a magnetic element. The first and second magnetic cores of the magnetic element are made by different materials. The second magnetic core contains ferrite material, so the loss of the second magnetic core is relatively low. Therefore, the causing loss of the magnetic element is decreased, and the conversion efficiency is increased.

It is another object of the present disclosure to provide a magnetic element. The directions of the magnetic fluxes generated on the two winding pillars of the first magnetic core are opposite, and the magnetic fluxes generated on the second magnetic core when the current flows through the windings are cancelled out by each other. Therefore, the causing loss of the magnetic element is decreased, and the conversion efficiency is increased.

In accordance with an aspect of the present disclosure, there is provided a magnetic element. The magnetic element includes a first magnetic core, a second magnetic core and two windings. The first magnetic core is made of a first material, the first magnetic core includes two winding pillars parallel to each other and two connecting parts, one of the connecting parts is connected to one end of one of the winding pillars and one end of the other one of the winding pillars respectively, and the other one of the connecting parts is connected to the other end of the one of the winding pillars and the other end of the other one of the winding pillars respectively, and the first magnetic core has a first permeability. The second magnetic core is made of a second material, the second magnetic core has a second permeability, and the first permeability is less than the second permeability. The two windings are wound on the two winding pillars of the first magnetic core respectively, when the current flows through the two windings, a closed magnetic

2

path is generated in the first magnetic core, the magnetic flux generated by the closed magnetic path flows through one of the winding pillars, one of the connecting parts, the other one of the winding pillars and the other one of the connecting parts in a direction, and the magnetic fluxes generated on the second magnetic core are cancelled out by each other. The first material contains an alloy material, and the second material contains a ferrite material.

The above contents of the present invention will become more readily apparent to those ordinarily skilled in the art after reviewing the following detailed description and accompanying drawings, in which:

BRIEF DESCRIPTION OF THE DRAWINGS

FIG. 1 is a schematic perspective view illustrating a magnetic element according to an embodiment of the present disclosure;

FIG. 2 is an exploded view illustrating the magnetic element of FIG. 1;

FIG. 3 is a schematic diagram illustrating the magnetic flux direction in the magnetic element of FIG. 1;

FIG. 4 is a schematic circuit diagram illustrating the magnetic element of FIG. 1 applied to an interleaved parallel circuit;

FIG. 5 is a schematic perspective view illustrating a magnetic element according to another embodiment of the present disclosure;

FIG. 6 is an exploded view illustrating the magnetic element of FIG. 5;

FIG. 7 is a schematic perspective view illustrating a magnetic element according to another embodiment of the present disclosure;

FIG. 8 is an exploded view illustrating the magnetic element of FIG. 7;

FIG. 9 is an exploded view illustrating a magnetic element according to another embodiment of the present disclosure; and

FIG. 10 is an exploded view illustrating a magnetic element according to another embodiment of the present disclosure.

DETAILED DESCRIPTION OF THE PREFERRED EMBODIMENT

The present disclosure will now be described more specifically with reference to the following embodiments. It is to be noted that the following descriptions of preferred embodiments of this disclosure are presented herein for purpose of illustration and description only. It is not intended to be exhaustive or to be limited to the precise form disclosed.

FIG. 1 is a schematic perspective view illustrating a magnetic element according to an embodiment of the present disclosure. FIG. 2 is an exploded view illustrating the magnetic element of FIG. 1. As shown in FIGS. 1 and 2, the magnetic element 1 can be applied to an interleaved parallel circuit (not shown), and the magnetic element 1 includes a first magnetic core 11, a second magnetic core 12 and two windings 13. The first magnetic core 11 is made of a first material. The first magnetic core 11 includes two winding pillars 14 parallel to each other and two connecting parts 113c and 114c. The connecting part 113c is connected to two ends of the two winding pillars 14, and the connecting part 114c is connected to the other two ends of the two winding pillars 14. The first magnetic core 11 has a first permeability. The second magnetic core 12 is made of a second material

and has a second permeability. The first material contains alloy material, and the second material contains a ferrite material. Since the second magnetic core **12** contains the ferrite material, the causing loss of the second magnetic core **12** is decreased, and the conversion efficiency is increased. The first magnetic permeability is smaller than the second magnetic permeability, so the first magnetic core **11** has better anti-saturation ability. The two windings **13** are wound on the two winding pillars **14** of the first magnetic core **11** respectively. In an embodiment, the winding directions of the two windings **13** are clockwise and counter-clockwise respectively, or are counterclockwise and clockwise respectively. In an embodiment, the two windings **13** are connected in series. When the current flows through the two windings **13**, a closed magnetic path is generated in the first magnetic core **11**. The magnetic flux generated by the closed magnetic path flows through one of the winding pillars **14**, one of the connecting parts **114c**, the other one of the winding pillars **14** and the other one of the connecting parts **113c** in a direction. The direction of the magnetic flux generated on the two winding pillars **14** of the first magnetic core **11** is opposite, and the magnetic fluxes generated on the second magnetic core **12** are cancelled out by each other. Therefore, the causing loss of the magnetic element **1** is decreased, and the conversion efficiency is increased.

The first magnetic core **11** includes a first assembly **111** and a second assembly **112** assembled to each other. The first assembly **111** has a first extension pillar **1131** and a second extension pillar **1132** extending from the connecting part **113c** of the first assembly **111**. The second assembly **112** has a first extension pillar **1141** and a second extension pillar **1142** extending from the connecting part **114c** of the second assembly **112**. The first extension pillar **1131** of the first assembly **111** and the first extension pillar **1141** of the second assembly **112** form one winding pillar **14**. The second extension pillar **1132** of the first assembly **111** and the second extension pillar **1142** of the second assembly **112** form the other winding pillar **14**. The second magnetic core **12** is an I-type magnetic core. The second magnetic core **12** is partially disposed between the first assembly **111** and the second assembly **112**. The bottom side **120** of the second magnetic core **12** is aligned with the first side **113a** of the first assembly **111** and the first side **114a** of the second assembly **112**. In other words, the bottom side **120** of the second magnetic core **12**, the first side **113a** of the first assembly **111** and the first side **114a** of the second assembly **112** are located on the same plane. The top side **121** of the second magnetic core **12** is aligned with the second side **113b** of the first assembly **111** and the second side **114b** of the second assembly **112**. In other words, the top side **121** of the second magnetic core **12**, the second side **113b** of the first assembly **111** and the second side **114b** of the second assembly **112** are located on the same plane. The first side **113a** and the second side **113b** of the first assembly **111** are opposite to each other. The first side **114a** and the second side **114b** of the second assembly **112** are opposite to each other. In an embodiment, the bottom side **120** of the second magnetic core **12** is protruded related to the first side **113a** of the first assembly **111** and the first side **114a** of the second assembly **112**, and the top side **121** of the second magnetic core **12** is protruded related to the second side **113b** of the first assembly **111** and the second side **114b** of the second assembly **112**. In another embodiment, the bottom side **120** of the second magnetic core **12** is concave related to the first side **113a** of the first assembly **111** and the first side **114a** of the second assembly **112**, and the top side **121** of the second magnetic core **12** is concave related to the second side **113b** of the first assembly **111** and the second side **114b** of the second assembly **112**.

second side **113b** of the first assembly **111** and the second side **114b** of the second assembly **112**. In further another embodiment, the bottom side **120** of the second magnetic core **12** is concave related to the first side **113a** of the first assembly **111** and the first side **114a** of the second assembly **112**, and the top side **121** of the second magnetic core **12** is protruded related to the second side **113b** of the first assembly **111** and the second side **114b** of the second assembly **112**. In further another embodiment, the bottom side **120** of the second magnetic core **12** is protruded related to the first side **113a** of the first assembly **111** and the first side **114a** of the second assembly **112**, and the top side **121** of the second magnetic core **12** is concave related to the second side **113b** of the first assembly **111** and the second side **114b** of the second assembly **112**.

In an embodiment, the conversion efficiency of the magnetic element **1** refers to the ratio of the output power **Po** to the input power **Pi** of the magnetic element **1**. Therefore, under the condition of the same input power **Pi**, if a higher output power **Po** can be obtained, it means that the conversion efficiency of the magnetic element **1** is improved.

Please refer to FIG. 3. FIG. 3 is a schematic diagram illustrating the magnetic flux direction of the magnetic element of FIG. 1. The direction of the magnetic flux is indicated by arrows. It can be seen from FIG. 3 that the magnetic fluxes generated on the second magnetic core **12** are cancelled out by each other, and the magnetic fluxes generated by the current flowing through the two windings **13** flow through the first magnetic core **11**.

Please refer to FIG. 4. FIG. 4 is a schematic circuit diagram of the magnetic element **1** of FIG. 1 applied to the interleaved parallel circuit **100**. The magnetic element **1** shown in FIG. 1 corresponds to two inductors L_{B1} and L_{B2} in the dashed frame shown in FIG. 4. The switching timings of the switches corresponding to the two inductors L_{B1} and L_{B2} have a phase difference of 180 degrees. The above-mentioned phase difference can be adjusted according to actual needs and is not limited thereto.

In an embodiment, the second magnetic core of the magnetic element is not limited to the aforementioned I-type magnetic core. Please refer to FIGS. 5 and 6. FIG. 5 is a schematic perspective view illustrating a magnetic element **1a** according to another embodiment of the present disclosure. FIG. 6 is an exploded view illustrating the magnetic element **1a** of FIG. 5. The elements of FIGS. 5 and 6 that are similar with those of FIGS. 1 and 2 are represented by the same reference numerals, and the detailed description thereof is omitted herein. In this embodiment, the second magnetic core **12a** is a U-type magnetic core, and the second magnetic core **12a** has a first section **121**, a second section **122** and a third section **123**. The first section **121** and the second section **122** are disposed oppositely. The third section **123** is connected between the first section **121** and the second section **122**, and a part of the third section **123** is protruded from the first section **121** and the second section **122**. The second magnetic core **12a** is assembled to the first magnetic core **11a** through the first section **121** and the second section **122**. Specifically, the first section **121** has a top side **121a** and a bottom side **121b** opposite to each other, and the second section **122** has a top side **122a** and a bottom side **122b** opposite to each other. The top side **121a** of the first section **121** and the top side **122a** of the second section **122** are assembled to a first protruding part **1110** and a second protruding part **1111** of the first assembly **111a** respectively. The bottom side **121b** of the first section **121** and the bottom side **122b** of the second section **122** are assembled to a first protruding part **1120** and a second

protruding part **1121** of the second assembly **112a** respectively. The first protruding part **1110** and the second protruding part **1111** of the first assembly **111a** protrude from opposite sides of the connecting part **113c** of the first assembly **111a** respectively, that is, the first protruding part **1110** and the second protruding part **1111** extend outward from the two opposite sides of the connecting part **113c** of the first assembly **111a** respectively. The first protruding part **1120** and the second protruding part **1121** of the second assembly **112a** protrude from opposite sides of the connecting part **114c** of the second assembly **112a** respectively, that is, the first protruding part **1120** and the second protruding part **1121** extend outward from the two opposite sides of the connecting part **114c** of the second assembly **112a** respectively. The first section **121** is connected between the first protruding part **1110** of the first assembly **111a** and the first protruding part **1120** of the second assembly **112a**. The second section **122** is connected between the second protruding part **1111** of the first assembly **111a** and the second protruding part **1121** of the second assembly **112a**. Therefore, the first magnetic core **11a** and the second magnetic core **12a** are assembled to each other. At least a part of the two windings **13** is disposed in the space formed between the first section **121**, the second section **122** and the third section **123** of the second magnetic core **12a**. In this embodiment, the first magnetic core **11a** and the second magnetic core **12a** form a special combination structure, and the second magnetic core **12a** is a U-type magnetic core, thereby increasing the inductance of the magnetic element **1a**.

In an embodiment, it is not limited to dispose the second magnetic core of the magnetic element in the above-mentioned manner. Please refer to FIGS. 7 and 8. FIG. 7 is a schematic perspective view illustrating a magnetic element **1b** according to another embodiment of the present disclosure. FIG. 8 is an exploded view illustrating the magnetic element **1b** of FIG. 7. The elements of FIGS. 7 and 8 that are similar with those of FIGS. 1 and 2 are represented by the same reference numerals, and the detailed description thereof is omitted herein. In this embodiment, the first magnetic core **11b** is a square-type magnetic and has a first surface **110** and a second surface **111** opposite to each other. The second magnetic core **12b** is a U-type magnetic core and is disposed on the first surface **110**. The two windings **13** are partially disposed between the first magnetic core **11b** and the second magnetic core **12b**, and the two windings **13** are wound on the two winding pillars **14b** of the first magnetic core **11b** respectively. The second magnetic core **12b** has a first section **16**, a second section **17** and a third section **18**. The first section **16** and the second section **17** are oppositely disposed. The third section **18** is connected between the first section **16** and the second section **17**. The first section **16** and the second section **17** are assembled to the two connecting parts of the first magnetic core **11b** respectively. The two windings **13** are partially disposed in a groove of the U-type second magnetic core **12b**. The groove is a space constructed by the first section **16**, the second section **17** and the third section **18** collaboratively. In this embodiment, the first magnetic core **11b** is a square-type magnetic core, and the second magnetic core **12b** is a U-type magnetic core. With the combination structure of the first magnetic core **11b** and the second magnetic core **12b**, the first magnetic core **11b** or the second magnetic core **12b** does not need to be disassembled during the assembly of the magnetic element **1b**, which makes the assembly of the magnetic element **1b** more convenient.

In an embodiment, the first assembly **111b** has a first outer side **19**, and the second assembly **112b** has a second outer

side **20**. The first outer side **19** and the second outer side **20** are aligned with the outer side of the first section **16** and the outer side of the second section **17** respectively.

In an embodiment, the second magnetic core **12b** is connected to the first magnetic core **11b**, that is, the first section **16** and the second section **17** are connected to the first surface **110** of the first magnetic core **11b**. The first magnetic core **11b** is partially disposed in the second magnetic core **12b**.

In an embodiment, the magnetic element includes a first magnetic core **11b** and two second magnetic cores **12b**. The two second magnetic cores **12b** are symmetrically disposed with respect to the first magnetic core **11b**, and the first magnetic core **11b** is disposed between the two second magnetic cores **12b**. The difference from the mentioned embodiment in which the second magnetic core **12b** is disposed on the first surface **110** shown in FIG. 8 is that the two second magnetic cores **12b** of this embodiment are disposed on the first surface **110** and the second surface **111** respectively. The first outer side **19** of the first assembly **111b** and the second outer side **20** of the second assembly **112b** are aligned with the outer sides of the first sections **16** of the two magnetic cores **12b** and the outer sides of the second sections **17** of the two magnetic cores **12b** respectively. Meanwhile, the magnetic fluxes on the two second magnetic cores **12b** generated by the current flowing through the two windings **13** are cancelled out by each other.

In an embodiment, the square-type first magnetic core is not limited to the one-piece structure shown in FIGS. 7 and 8. The square-type first magnetic core can also be composed of a U-type core and an I-type core or two U-type cores. Please refer to FIGS. 9 and 10. FIG. 9 is an exploded view illustrating a magnetic element **1c** according to another embodiment of the present disclosure, and FIG. 10 is an exploded view illustrating a magnetic element **1d** according to another embodiment of the present disclosure. The elements of FIGS. 9 and 10 that are similar with those of FIG. 7 are represented by the same reference numerals, and the detailed description thereof is omitted herein. In the embodiment of FIG. 9, the square-type first magnetic core **11c** is formed by assembling an I-type magnetic core **110c** and a U-type magnetic core **111c**. In the embodiment shown in FIG. 10, the square-type first magnetic core **11d** is formed by assembling two U-type magnetic cores **110d**.

From the above descriptions, the present disclosure provides a magnetic element. The first and second magnetic cores of the magnetic element are made by different materials. The second magnetic core contains ferrite material, so the loss of the second core is relatively low. The directions of the magnetic fluxes generated on the two winding pillars of the first magnetic core are opposite, and the magnetic fluxes generated on the second magnetic core when the current flows through the windings are cancelled out by each other. Therefore, the causing loss of the magnetic element is decreased, and the conversion efficiency is increased.

While the disclosure has been described in terms of what is presently considered to be the most practical and preferred embodiments, it is to be understood that the disclosure needs not be limited to the disclosed embodiment. On the contrary, it is intended to cover various modifications and similar arrangements included within the spirit and scope of the appended claims which are to be accorded with the broadest interpretation so as to encompass all such modifications and similar structures.

What is claimed is:

1. A magnetic element for an interleaved parallel circuit, comprising:

a first magnetic core made of a first material, wherein the first magnetic core comprises two winding pillars, two connecting parts, a first assembly and a second assembly, the two winding pillars are parallel to each other, one of the connecting parts is connected to two ends of the two winding pillars, the other one of the connecting parts is connected to the other two ends of the two winding pillars, the first magnetic core has a first permeability, and the first assembly and the second assembly are assembled to each other;

a second magnetic core made of a second material, wherein the second magnetic core has a second permeability, the first permeability is less than the second permeability, and the second magnetic core is partially disposed between the first assembly and the second assembly; and

two windings wound on the two winding pillars of the first magnetic core respectively, wherein when the current flows through the two windings, a closed magnetic path is generated in the first magnetic core, the magnetic flux generated by the closed magnetic path flows through one of the winding pillars, one of the connecting parts, the other one of the winding pillars and the other one of the connecting parts in a direction, and the magnetic fluxes generated on the second magnetic core are cancelled out by each other;

wherein the first material contains an alloy material, and the second material contains a ferrite material.

2. The magnetic element according to claim 1, wherein the second magnetic core is an I-type magnetic core.

3. The magnetic element according to claim 1, wherein the second magnetic core is an U-type magnetic core.

4. The magnetic element according to claim 3, wherein the second magnetic core has a first section, a second section and a third section, the first section and the second section are oppositely disposed, the third section is connected between the first section and the second section, and the second magnetic core is assembled to the first magnetic core through the first section and the second section.

5. The magnetic element according to claim 4, wherein the first section has a top side and a bottom side opposite to each other, the second section has a top side and a bottom side opposite to each other, the top side of the first section and the top side of the second section are assembled to a first protruding part and a second protruding part of the first assembly respectively, the bottom side of the first section and the bottom side of the second section are assembled to a first protruding part and a second protruding part of the second assembly respectively, and at least a part of the two windings is disposed in a space formed between the first section, the second section and the third section.

6. The magnetic element according to claim 1, wherein the first magnetic core is a square-type magnetic core, and the second magnetic core is a U-type magnetic core.

7. The magnetic element according to claim 6, wherein the first magnetic core has a first surface, the second magnetic core is disposed on the first surface, the two windings are partially disposed between the first magnetic core and the second magnetic core, the second magnetic core has a first section, a second section and a third section, the first section and the second section are oppositely disposed, the third section is connected between the first section and the second section, and the first section and the second section are assembled to the two connecting parts of the first magnetic core respectively.

8. The magnetic element according to claim 6, wherein the first magnetic core is composed of a U-type magnetic core and an I-type magnetic core.

9. The magnetic element according to claim 6, wherein the first magnetic core is composed of two U-type magnetic cores.

10. The magnetic element according to claim 1, wherein the magnetic element corresponds to two inductors of the interleaved parallel circuit, and switching timings between switches corresponding to the two inductors have a phase difference of 180 degrees.

* * * * *
